5 SHEETS—SHEET 3.

This technical cross-sectional diagram illustrates a bridge pier foundation. The foundation is a rectangular structure with a central cavity. The cavity is filled with a material labeled '12'. The base of the foundation is supported by a series of piles, some of which are labeled '21' and '22'. The foundation is surrounded by a layer of material labeled '11'. The top of the foundation is shown with a cross-hatch pattern. Several labels are present: '12' is located on the left side of the cavity, '21' is on the right side, '22' is at the bottom right, '11' is in the center of the base, '23' is at the top center, '24' is on the left side of the cavity, '29' is on the right side of the cavity, '30' is at the bottom left, '14' is at the bottom right, and '14 14' is at the bottom far right. There are also numerical labels '6', '8', and '7' scattered around the diagram.

UNITED STATES PATENT OFFICE.

LUTHER L. KNOX, OF BEN AVON, PENNSYLVANIA, ASSIGNOR TO KEYSTONE FURNACE CONSTRUCTION COMPANY, OF PITTSBURG, PENNSYLVANIA, A CORPORATION OF PENNSYLVANIA.

FURNACE.

No. 919,027.

Specification of Letters Patent.

Patented April 20, 1909.

Application filed June 17, 1908: Serial No. 438,967.

To all whom it may concern:

Be it known that I, LUTHER L. KNOX, of Ben Avon, Allegheny county, Pennsylvania, have invented a new and useful Improvement in Furnaces, of which the following is a full, clear, and exact description, reference being had to the accompanying drawings, forming part of this specification, in which—

Figures 1 and 2 are side elevations of a portion of an open hearth furnace embodying my invention, taken respectively from the charging and tapping sides; Fig. 3 is a plan view of the same partly in section, the portion in section being taken on the line III—III of Fig. 1; Fig. 4 is a central vertical section of the furnace; Figs. 5, 6, 7, 8, 9 and 10 are detail views hereinafter more particularly referred to, showing the arrangement of the cooling boxes and the circulating connections therefor; and Fig. 11 is a detail view showing a slight modification.

My invention has relation to improvements in furnaces, and is applicable to various kinds of furnaces, such as open hearth furnaces, melting furnaces, heating furnaces, etc., and is designed to provide means for protecting the furnace walls, or such portions thereof as may be necessary, from the more or less rapid destruction which ordinarily takes place in furnaces of this class.

To this end my invention consists in the provision of means for water-cooling the various portions of the furnace walls which are most subject to the destructive action, such as the side walls, the end walls, the roof, the ports, the up-takes, etc.

The precise nature of my invention will be best understood by reference to the accompanying drawings, in which I have illustrated its embodiment in an open hearth furnace, it being premised, however, that the details of construction and arrangement may be variously changed by those skilled in the art without departing from the spirit and scope of my invention, and that the invention is equally applicable to other types of furnace in the general class above stated.

In the drawings, the numeral 2 designates the side walls of an open hearth furnace, provided with the usual charging doors 3, mending door 4, and tap opening 5.

6 designates the hearth of the furnace, and 7 the arched roof.

8 is the gas port at one end of the furnace,

which is connected with the up-take 9 leading from the slag pocket 10, and 11 is the air port connected with the air up-take 12, leading from the slag pocket 13.

In accordance with my invention, I build into the brickwork of the furnace at the parts thereof which are to be protected by the water-cooling a plurality of hollow water-cooling boxes or castings. These boxes may be arranged in various ways, according to the particular nature and construction of the furnace. In the furnace shown in the drawings, I have shown the side walls of the furnace as having a plurality of these boxes, indicated at 14, set into the brickwork of each of the side walls between the buck-stays 15 and extending partially through such walls, as shown in Fig. 4. Preferably, each of these boxes or castings is of substantially the thickness of a single brick, and the boxes are built into the wall one above the other, as shown; each box being, however, readily removable for renewal should it become burned out. I also prefer to place at each side of the buck-stays and between the buck-stays and the adjacent door at the charging side of the furnace, a cooling box or casting 16, which extends parallel with the edges of the door opening, and which, together with the water cooled frames 17, which are preferably employed at these openings in accordance with my former patents, effectively prevent the destruction of the adjacent brick-work.

Vertically extending boxes or castings such as shown at 18, may also be built into the side walls between the buck-stays as shown in Fig. 1. I also preferably employ the cooling boxes or castings 19, which extend into the side walls immediately below the skew-back channels 20. Similar boxes or castings 21 are placed in the side walls of the air ports at each side of the furnace, as shown. At the tapping side of the furnace, in addition to the short boxes 14 between the buck-stays, longer boxes 22 are built into the brick-work between the buck-stays, one above another, as shown. In a similar manner, the end wall of the gas up-take 9 is protected by a series of cooling boxes 23 built therein, and which are preferably of the form shown in Fig. 3.

The roof of the furnace is protected by a plurality of small boxes 24, which are built therein, each of which is preferably of the size of one or more bricks. These boxes 24 pref-

erably extend through the roof arch, as shown in Fig. 4, and are separately removable from the top of the arch.

The arch between the gas and air ports, 5 may be constructed and protected in any suitable manner. In the construction and arrangement, shown in the present instance, this arch consists of a hollow arched casting, which is built into the walls of the furnace, 10 and which is formed with the skew-backs 26 supporting the refractory material 27 which constitutes the roof of the gas port. The casting 25 also supports the refractory material 28, which constitutes the floor of the 15 air port. The arch as thus constructed and arranged is a permanent part of the furnace, and is not intended for removal.

The various cooling boxes or castings can be connected in any suitable manner to provide 20 for proper circulation of water there-through, the connections being provided with detachable unions so as to permit the ready removal and replacement of any particular box or boxes.

25 Figs. 5 and 8 show one method of connecting up the boxes 24 in the roof of the furnace, each box having a supply connection 29 with a supply pipe 30, suitable valves 31 being provided in these connections. In order to 30 permit the water to be shut out of any one of these boxes without affecting its circulation through the others, each pair of boxes is also provided with the pipe connection 32 having the valves 33 and 34. If it becomes necessary 35 to remove and replace either box of any pair, it will readily be seen that the valves 31 and 33 may be operated to shut out the water from that particular box without interfering with its circulation through the other box of the pair. The boxes 24 may be provided with any suitable interior construction to insure a proper circulation of water therein. Thus, as shown in Fig. 9, they may have a 40 depending partition wall or baffle 35 whose lower edge terminates above the bottom of the box. The water entering the box through the connection 29 at one side of this wall or baffle passes through one end portion of the box, and thence underneath the wall or 45 baffle into the other end portion of the box and to the outlet connection. Each of these outlet connections is preferably provided with an escape pipe 24*, by means of which any steam which may form in the box may 50 be allowed free escape.

55 Figs. 6 and 7 indicate one method of connecting up the boxes 14 in the side walls of the furnace, the boxes in each vertical row being connected in series by the connections 60 36 having each a detachable union 37.

Fig. 10 shows in detail one of the boxes 23 provided with the circulating connections 38.

It will be understood that the precise arrangement and form of the cooling boxes 65 will necessarily depend upon the particular

character of the furnace, its size, etc., and may vary therefore in each case according to these circumstances. The general nature of my invention will, however, be fully understood and appreciated from the embodiment 70 thereof, which I have illustrated and above described. It will be seen that I provide for the water-cooling of all portions of the furnace walls which are ordinarily most subject to the destructive action of the heat, these 75 being portions of the side walls, the furnace roof or arch, the gas up-take, and the arch between the gas and air ports. By effecting the water-cooling by means of boxes or castings, each of which has a dimension equal to 80 one or more bricks, it will be seen that these castings or boxes can be readily built into the walls, as they are built up, without any cutting of brick, while at the same time any box can be readily removed without endangering 85 the stability of the wall. If desired, a supporting arch, such as indicated at 39 in Fig. 11, may be built over each of these removable boxes, but this is ordinarily not required. It will also be seen that while the arrangement of the boxes as shown and described 90 will provide for the effective cooling and protection of the furnace walls, the incoming air and gas for the furnace will not be appreciably cooled.

I claim:

1. A regenerative reversing furnace, having hollow water-cooled boxes or castings built into its walls at intervals, said boxes having dimensions equal to those of one or more bricks, whereby they may be interposed 100 in the courses of bricks forming said walls, without cutting the bricks, substantially as described.

2. A regenerative reversing furnace having hollow water-cooled removable boxes or castings built into its walls at intervals, said boxes having dimensions equal to those of one or more bricks, whereby they may be interposed in the courses of bricks forming said 110 walls, without cutting the bricks, substantially as described.

3. A regenerative, reversing furnace having a plurality of water-cooled boxes built into its side walls, said boxes extending partially through the said walls from the outer surfaces thereof, and having each a thickness equal to the thickness of one or more bricks, whereby they may be set into the courses of 115 bricks forming the said walls without cutting or breaking the bricks, substantially as described.

4. A regenerative, reversing furnace having an uptake provided with a plurality of water-cooled boxes set into a wall thereof, 125 said boxes being each of the thickness of one or more bricks, substantially as described.

5. A regenerative, reversing furnace having a port provided with a plurality of water-cooled boxes set into a wall thereof, said 130

boxes each of the thickness of one or more bricks, substantially as described.

6. A regenerative, reversing furnace, having its side walls and its roof each provided with a plurality of hollow cooling boxes or castings built into the brick work thereof between the courses of bricks; substantially as described. 40

7. A furnace of the class described having an arch separating its gas and air ports, said arch consisting of a hollow arch casting built into the brick-work of the furnace and carrying skew-backs which support a refractory roof or lining for the gas port and also a refractory covering which forms the floor of the air port; substantially as described. 15

8. A regenerative, reversing furnace wall composed in part of refractory bricks and in part of hollow water-cooled boxes or castings 20 interposed at intervals in the courses of bricks, and of the same thickness as one or more bricks, substantially as described.

9. A regenerative, reversing furnace, having its side and port walls, and its roof each provided with a plurality of hollow cooling boxes or castings built into the brickwork thereof between the courses of bricks; substantially as described. 25

10. A regenerative, reversing furnace, having a wall thereof provided with a plurality of hollow cooling boxes or castings built in to the brick work thereof between the courses of bricks; substantially as described. 30

11. In a reversing regenerative furnace having an up-take port whose outer wall is

of less thickness than the adjacent parts of the end wall of the furnace, said outer wall being formed in part of refractory material and in part of cooling boxes built into the refractory material one above another; substantially as described. 40

12. A reversing, regenerative furnace having a plurality of up-take ports, the outer wall of each of said ports being formed in part of refractory material and in part of cooling boxes built into the refractory material one above another, and the different series of cooling boxes being separated from each other by intervening wall portions wholly of refractory materials; substantially 50 as described.

13. A reversing, regenerative furnace having a plurality of up-take ports, the outer wall of each of said ports being formed in part of refractory material and in part of cooling boxes built into the refractory material one above another, and the different series of cooling boxes being separated from each other by intervening wall portions wholly of refractory materials, said intervening portions being of greater thickness than the outer walls of the uptake ports; substantially as described. 55

In testimony whereof, I have hereunto set my hand.

LUTHER L. KNOX.
